(57) **CLAIM**

The ornamental design for a chafing pan, as shown and described.

DESCRIPTION

FIG. 1 is a top perspective view of a first embodiment of the chafing pan of this invention;

FIG. 2 is a bottom perspective view of the chafing pan of FIG. 1;

FIG. 3 is a front view of the chafing pan of FIG. 1, with the back view being a mirror image thereof;

FIG. 4 is a right-side view of the chafing pan of FIG. 3, with the left-side view being a mirror image thereof;

FIG. 5 is a top view of the chafing pan of FIG. 3;

FIG. 6 is a bottom view of the chafing pan of FIG. 3;

FIG. 7 is a top perspective view of a second embodiment of the chafing pan of this invention;

FIG. 8 is a bottom perspective view of the chafing pan of FIG. 7;

FIG. 9 is a front view of the chafing pan of FIG. 7, with the back view being a mirror image thereof;

FIG. 10 is a right-side view of the chafing pan of FIG. 9, with the left-side view being a mirror image thereof;

FIG. 11 is a top view of the chafing pan of FIG. 9; and,

FIG. 12 is a bottom view of the chafing pan of FIG. 9.
